(57) CLAIM

An ornamental design for a beverage holder, as shown and described.

DESCRIPTION

FIG. 1 is a perspective view of the rear and side of my beverage holder showing my design.

FIG. 2 is a left side view thereof.

FIG. 3 is a right side view thereof.

FIG. 4 is a rear view thereof.

FIG. 5 is a top view thereof.

FIG. 6 is a bottom view thereof; and,

FIG. 7 is a side view similar to FIG. 2 showing the beverage holder attached to a pole and holding a bottle, both shown in dotted line. The pole and bottle shown in dotted line form no part of the design.
